(57) **CLAIM**

The ornamental design for a bottle, as shown and described.

DESCRIPTION

FIG. 1 is a front perspective view of a bottle in accordance with the present invention.

FIG. 2 is a side elevation view of the bottle of FIG. 1, the other side elevations are the same except for the threading on the neck.

FIG. 3 is a top view of the bottle of FIG. 1; and, FIG. 4 is a bottom view of the bottle of FIG. 1. The broken lines shown in FIGS. 1-3 of the neck, threads, and cap are for illustrative purposes only and form no part of the claimed design.

1 Claim, 2 Drawing Sheets
